UNITED STATES PATENT OFFICE

WILFORD C. MACFADDEN, OF FOX CHASE, PENNSYLVANIA, ASSIGNEE TO HUGH H. RBY,
OF PHILADELPHIA, PENNSYLVANIA

SOCKET FOR TUBES

Original application filed February 21, 1928, Serial No. 341,695. Divided and this application filed November 1, 1930. Serial No. 492,817.

My invention relates to an electrical socket for the prongs of a plug-in device, such as a plug terminus of a cable or a vacuum tube. This application is a division of my application, Serial Number 341,695, upon which Patent 1,780,778 issued November 4, 1930.

An object of my invention is to provide a simplified and inexpensive socket especially adapted to ready assembly and large quantity production.

A further object of my invention is to mount metal contact members upon a punched plate of insulation material by means of a single fastener member and extending one end of each contact member to form a soldering lug.

A further object of my invention is to provide a non-integral guiding means in combination with a socket for the purpose of overlying portions of fastenings of the metallic contact members in insulating relation.

A further object of my invention is to provide a laminated socket comprising an insulating guide member or lamination adapted to cooperate with a fastening means for securing the laminations in assembled relation.

My invention resides in the structures and features herein after described and claimed.

Referring to the drawing which illustrates one form my invention may take:—

Figure 1 shows a plan view of my socket in assembled relation in a receiving set.

Figure 2 is a section of Figure 1 taken upon the line 2—2.

Figure 3 is a sectional perspective partly broken away and omitting the guiding and reinforcing disc or boss, intended to illustrate the way in which the clips are held in place between the plates.

Like numerals refer to like parts in all figures of the drawing. The stamped plate of insulation material 1 has a group of passages 2 adapted to receive the prongs of a vacuum tube. Secured to the underneath side of plate 1 is a second plate 3 having apertures 4 through which are mounted in depending relation metallic contact structure 5.

Each contact structure includes contact

elements 6 that are resiliently supported by U-shaped element 7. Contact elements 6 are free to adapt themselves to the contour of the inserted prongs of a plug-in device and are integral with the U-shaped portion 55 7. The upper (outer) ends of the U-shaped members are provided with tail extensions 8, 9 bent at right angles to the arms of the U. These extensions support the contact structure and are clamped between the plates 1 60 and 3. The extension 8 is clamped at its end and the extension 9 is clamped at an intermediate portion permitting its end 10 to protrude through hole 11 in plate 3. The protruding part is used as a soldering lug for attachment of a wire so as to include it within an electric circuit. The extreme end of the tail extension 8 is provided with an upwardly extended (laterally with respect to the planes of the plates) portion 12 which fits into the small hole 13 in the upper plate 1.

The raised non-integral disc or boss 15 is positioned upon the top of the upper plate in such relation that the holes 2 for the prongs of the plug-in device are arranged substantially around the outside circumference of this boss, thus adapting the boss to act as a guide member when inserting vacuum tubes or plug-in devices. This boss 75 and plate members 1 and 3 are centrally perforated to receive a securing member such as rivet 17 which is common to all three and which clamps boss 15 and plates 1 and 3 firmly together, holding the contact structure in clamped relation.

It is frequently desirable to color the disc or boss or otherwise mark the disc or boss 15 to correspond with the type of tube to be used. However, this is no part of the present invention, being disclosed and claimed in my Patent No. 1,771,094 issued July 22, 1930. It is thus seen that the insulating washer or boss 15 serves as a 90 strengthening clamp member to assist in securing plates 1 and 3 together and overlies the aperture 13 and end 12.

The assembled socket is secured to the metallic chassis 19 of a radio set, as for example, in such manner that top plate 1 is flush with 100

the opening 21 in metal plate 19. While I have illustrated the guide disc or boss 15 as centrally disposed with respect to holes 2 it is obvious to one skilled in the art that 5 the guide boss could be mounted in other relation with respect to holes 2 in overlying and insulating relation with the contact structure. It is likewise obvious that the contact structure could be supported entirely 10 from a point outside the area bounded by the prong apertures 2 as shown in my parent application.

In view of my invention and disclosure other variations and modifications to meet 15 individual choice or particular need will doubtless become evident to those skilled in the art. I therefore, claim all such modifications in so far as they fall within the reasonable spirit and scope of my invention.

20 What I claim as new is:

1. In a socket receptacle, a plate of insulation material having a group of passages to receive the prongs of a plug-in device, contact structure for said prongs depending 25 from said plate adjacent said passages extending thru said plate and having fastenings, a second plate of insulation material perforated to correspond with the passages of the first, superimposed, on the first plate 30 on the side opposite the contact terminals and engaging the plurality of said fastenings, a disc of insulation material overlying said second plate and a plurality of the fastenings, said disc being centrally disposed 35 with respect to said passages, and means for securing said plates and said disc together in assembled relation.

2. In a socket receptacle, a plate of insulation material having a group of passages 40 to receive the prongs of a vacuum tube, contact structure for said prongs depending from said plate extending thru said plate and having metallic fastenings, one set of fastenings having portions lying outside 45 said group of passages, and another set having portions inside said group, a second plate of insulation material superposed on and secured to said first plate and covering a plurality of said fastening portions, and a guiding insulating disc for the prongs of said 50 tube secured to said plates and overlying the inside group of said fastening portions.

3. An integral spring connector for a pin terminal of a plug-in device comprising an 55 elongated sheet metal U-strip having the outer ends of the strip bent at an angle to the adjoining arms of the U, the ends comprising, one an intermediate portion having united integrally therewith a soldering connection, 60 and the other an end to be clamped, contact members laterally off-set, one from each arm, and substantially co-extensive therewith, an insulation plate perforated to receive the arms of the U, a second insulation plate perforated for passage of the pins and

superimposed on said first plate so that the intermediate portion and the end are clamped between the plates, a disc reinforcing the second plate and stiffening it for clamping of the end and means for holding 70 the two plates and disc together.

4. In a socket receptacle, a plurality of clips, a pair of plates of insulation material, one plate having spaced openings for contact devices and the other perforated in line with the openings, contact structure connected with said clips, each comprising a U-shaped contact carrying member extending through one of the openings and having the ends of the U spread away from each other, 80 one inwardly and the other outwardly, one end comprising an intermediate portion of that clip and both ends clamped between the two plates, and a central fastening for the plates bringing substantially equal pressure 85 upon the inwardly directed U-ends about the fastening.

5. In a socket receptacle, a plurality of clips, a pair of plates of insulation material, one plate having spaced openings, intermediate portions of the clips held between the plates and the other apertured in line with the openings, contact structure connected with said portions, each comprising a U-shaped contact carrying member extending through one of the openings and having the ends of the U spread away from each other, 90 one inwardly and the other outwardly, one end comprising the intermediate portion of that clip and both ends clamped between the two plates, a central fastening for the plates bringing substantially equal pressure upon the inwardly directed U-ends about the fastening and reinforcing pressure means 95 concentric with respect to the fastener and held by the fastening to increase the pressure upon the inwardly directed ends.

6. In a socket receptacle, a plurality of clips a pair of plates of insulation material, one plate having spaced openings, intermediate portions of the clips held between the plates and the other perforated in line with the openings, contact structure connected with said portions, each comprising a U-shaped contact carrying member extending 110 through one of the openings and having the ends of the U spread away from each other, one inwardly and the other outwardly, one end comprising the intermediate portion of that clip and both ends clamped between the two plates, a central fastening for the plates bringing substantially equal pressure upon the inwardly directed U-ends about the fastening, reinforcing pressure means concentric with respect to the fastener and held 115 by it to increase the pressure upon the inwardly directed ends and outer fastenings holding the two plates together outside of the contact carrying members.

7. In a socket receptacle, a pair of plates 130

of insulation material having openings in one of the plates and the other being apertured in line with the openings, U-shaped contact carrying members, one in each of the 5 openings and having ends extending in opposite directions between the plates one set inwardly and the other set outwardly on opposite sides of the openings so that the two ends are clamped between the plates, a disc 10 reinforcement for the plates located on the inner sides of the U and assisting in holding the adjoining ends of the contact carrying members and acting as guides for the plugs to be inserted therein and central retaining 15 means common to the disc and plates.

8. In a socket receptacle, a plate of insulation material having a group of passages to receive the prongs of a vacuum tube, contact structure for said prongs depending from 20 said plate, extending through said plate and having metallic fastenings, one set of fastenings having portions extending outwardly outside said group of passages and including intermediate portions and terminal soldering 25 portions, and another set having portions extending inwardly inside said group, a second plate of insulation material superimposed on and secured to said first plate, covering and clamping said outside and inside 30 fastening portions and apertured in line with the passages of the first plate, projections upon the inwardly extending portions each fitting into a space in one of said plates to lock these portions against withdrawal 35 parallel to the planes of the plates, a disc adjoining and supporting the second plate to additionally clamp the inwardly extending fastening portions and means for holding the disc and plates together.

40 In testimony whereof I affix my signature.

WILFORD C. MacFADDEN.
